FLAME HARDENING

John J. Crowe, Westfield, N. J., assignor to Air Reduction Company, Incorporated, New York, N. Y., a corporation of New York

Application April 2, 1940, Serial No. 327,407

14 Claims. (Cl. 148—21)

This invention relates to flame hardening, and more particularly to methods and apparatus by which a work-piece can be hardened to a uniform depth in spite of variations in the section of metal.

In flame hardening operations, the heat of high-intensity flames, such as oxyacetylene flames, is applied to the surface of the work-piece and the metal is heated above its critical temperature on the surface and for a limited depth below the surface. The depth to which the metal is heated above its critical temperature depends upon a number of factors including the intensity of the heating jets, the number of jets, the length of time that the heat is applied, and the mass of underlying metal into which heat flows by conduction.

It is an object of this invention to prevent variation in the depth of hardness as a result of differences in the mass of underlying metal at different parts of a workpiece, and this result is obtained by producing compensating variations in one or more of the other factors that effect the depth of hardening.

In the preferred embodiment of this invention different numbers of flame jets are used to compensate for differences in the mass of metal into which heat is lost by conduction. In this way the depth of metal that remains heated above its critical temperature can be kept substantially constant throughout the length of a section. The invention changes the number of flames in accordance with their longitudinal displacement during a progressive flame hardening operation. The same result can be obtained by changes in the intensity of the flames, but variation in the number of flames can be obtained more advantageously in practice.

Other objects, features and advantages of the invention will appear or be pointed out as the specification proceeds.

In the accompanying drawings, forming part hereof:

Fig. 1 is a perspective view, partly diagrammatic, illustrating the manner in which a round body is hardened in accordance with this invention.

Fig. 2 is a perspective view showing apparatus for hardening a flat work-piece in accordance with this invention.

Fig. 3 is an enlarged vertical section through the torch block on the line 3—3 of Fig. 2.

Fig. 4 is an enlarged perspective view of one end of the torch shown in Fig. 2, the view being

taken from such an angle that the bottom face of the torch block is visible.

Figs. 5—9 are diagrammatic elevations, on a reduced scale, showing the variation in the number of flames operating while the torch block of Fig. 2 is moved progressively along the work-piece.

Fig. 1 shows a torch block 11 in which are two separate distributing chambers, a longitudinal chamber 12 and a transverse chamber 13. A mixture of oxygen and fuel gas, preferably an oxyacetylene mixture, is supplied to the longitudinal distributing chamber 12 by tubing 15. A similar gas mixture is supplied to the transverse distributing chamber 13 by tubing 16 that communicates with the chamber 13 through a passage 17 in the torch block 11.

A row of evenly spaced flame jet orifices 18 open through the top face of the torch block 11 and at their lower ends open into the distributing chamber 12. A similar transverse row of flame jet orifices 19 leading from the chamber 13 open through the top face of the torch block.

The supply of gas to the tubing 15 and 16 is controlled by quick-acting shut-off valves 21 and 22, respectively. Fuel gas is supplied through a tube 23 and oxygen through a tube 24 to an inlet pipe 26 that communicates with the valve 21 on the upstream side. Fuel gas and oxygen flow to the valve 22 through conduits similar to the tubes 23, 24 and indicated by the same reference characters. There is a valve 27 in each of the tubes 23, 24 for adjusting the flow of fuel gas or oxygen.

The shut-off valves 21 and 22 are normally closed, by spring or weight bias, and are opened by upward displacement of valve-operating plungers 28 and 29, respectively. The plunger 28 is displaced by a cam 30 secured to a cam shaft 32 that is rotated by a timer 33. Another cam 34 secured to the shaft 32 displaces the plunger 29.

The torch block 11 has a distributing chamber 36 from which quenching fluid, such as water, is discharged through jet orifices 37 that open through the bottom face of the torch block. The quenching fluid is supplied through a pipe 38, shut-off valve 39, and tubing 40. The shut-off valve 39, which is normally closed, has an operating plunger 41 that is displaced by a cam 42 secured to the same shaft 32 as the gas control cams.

A work-piece 44, which is to be hardened on the inside, has an external flange 45 that makes the mass of the work-piece much greater at its

left-hand end. Before placing the torch 11 in the work-piece, the torch is lighted and with the valves 21 and 22 open, the adjusting valves 27 are set to obtain the desired supply of fuel gas and oxygen. The flames are then shut off by means of the quick-acting valves 21 and 22, and the torch 11 is placed in the position shown in Fig. 1.

The timer 33 is started and the cam 34 opens the valve 22 and causes gas to flow to the flame jet orifices 19. The jets from these orifices are lighted and heat the metal in the region of the flange 45. After a definite time interval, the cam 30 opens the valve 21 and permits gas to flow to the flame jet orifices 18. The jets from these orifices are ignited by the other flames and the inside of the work-piece is heated by all of the flames. The work-piece is rotated rapidly during the entire time that it is being heated in order to distribute the heat uniformly around the entire angular extent of the inside surface.

The cams 30 and 34 are so designed that with a given speed of rotation of the shaft 32 by the timer 33, the work-piece 44 is heated above the critical temperature of the metal for a predetermined depth, and for a uniform depth along the entire width of the work-piece because the additional heat put into the work-piece in the region of the flange 45 compensates for the heat lost by conduction into the additional mass of metal at the left end of the work-piece. The time that the cams 30 and 34 hold the valves 21 and 22 open depends upon the heating effectiveness of the torch. Each of the flame jets is a separate heating agency and the intensity of the flame systems and the heating effectiveness of the torch depend not only upon the size of these flames but upon how closely they are spaced. The cams coordinate the heating time with the intensity of the flame systems to obtain the necessary heating of the work-piece, the set of cams being designed for a particular work-piece that is produced in quantity.

As soon as the cams 30 and 34 have turned far enough to cause the valves 21 and 22 to close, the cam 42 immediately opens the valve 39 and causes fluid from the quenching jet orifices 37 to cool the rapidly-rotating work-piece quickly and produce the desired hardness.

The application of this invention to a progressive flame hardening operation is illustrated in Fig. 2. A self-propelled torch carriage 48 has front wheels 49 driven by a motor 50, and rear wheels 51, that run on rails 52 attached to a supporting table 53. The carriage travels along the track at preferably uniform speed.

A torch-supporting bar 55 slides in a bearing block 56 on top of the carriage. A rack 57 extends along the length of the bar 55 and the bar is shifted lengthwise in the bearing block 56 by a pinion that meshes with the rack and that is turned by a shaft 59. There is a hand-wheel 60 at the upper end of the shaft 59.

A bracket 62 near one end of the supporting bar 55 is connected to a torch block 63 and holds the torch block 63 spaced from a work-piece 64. The block 63 extends across as much of the width as is to be hardened, which is the full width of the work-piece 64 in Fig. 2.

The structure of the torch block 63 is shown in Figs. 3 and 4. There are four parallel distributing chambers 66, 67, 68 and 69 extending lengthwise in the torch block for substantially the entire length of the block. A row of jet orifices 71, 72, 73 and 74 extend from the cham-

bers 66, 67, 68 and 69, respectively, and through the bottom face of the torch block 63 as shown in Fig. 4. The chambers 66, 67, 68 and 69 are at different levels in the torch block to permit the rows of jet orifices to be located closer together.

A mixture of oxygen and fuel gas is supplied to the distributing chambers 66 and 68 through vertical passages 76 and 78, respectively, in one end of the torch block, and a similar mixture is supplied to the chamber 67 through a vertical passage 77 at the other end of the torch block. Quenching fluid, such as water, is supplied to the distributing chamber 69 through a passage 79 in the end of the torch block with the passage 77.

The supply of fluids to the torch 63 in Fig. 2 is controlled by cam-operated valves similar to those shown in Fig. 1 and the pipes and tubing and gas-flow adjusting valves are indicated by the same reference characters as in Fig. 1. These valves are housed within the front of the carriage 48 in Fig. 2, and there are three gas shut-off valves instead of two as shown in Fig. 1. The valves are identical, however, and the additional gas line is indicated by the reference character 81. The tubing 15, 16, 81 and 40 connects with the top of the torch block 63 in register with the passages 77, 78, 76 and 79, respectively.

The cams that control the supply of fluids to the tubing 15, 16, 81 and 40 are on a common cam shaft 32, but instead of a timer, such as shown in Fig. 1, the cam shaft 32 of Fig. 2 is turned by a pinion 83 keyed to one end of the cam shaft 32 and meshing with a rack 84 that is parallel to the rails 52 and fastened by brackets to the supporting table 53.

The advantage of this rack and pinion operation of the cam shaft 32, in progressive hardening, is that the cam operation is dependent upon the displacement of the torch carriage and the valves are operated when the carriage and torch reach predetermined positions along their course of travel regardless of the speed at which the carriage moves.

The particular shape of the cams used to operate the valves on the torch carriage of Fig. 2 will be evident from the operation illustrated in Figs. 5-9.

During the first part of the hardening operation the torch block 63 moves to the right across the top of the work-piece 64 with flame jets 73' issuing from the third row of orifices 73 and quenching jets 74' issuing from the fourth row of orifices 74. No gas is supplied to the first and second rows of orifices 71 and 72.

Fig. 6 shows the torch 63 as it approaches the section where the thickness of the work-piece begins to increase. At this location the cams cause the second row of orifices 72 to be supplied with an oxy-fuel gas mixture and flame jets 72' are lighted and increase the heating effectiveness of the torch to compensate for the added heat loss by conduction to the additional mass of metal.

In Fig. 7 the torch is shown as it reaches the section where the work-piece 64 attains its maximum thickness and at this section the oxy-fuel gas mixture is supplied to the remaining row of jet orifices 71 to produce the heating flames 71' and bring the torch 63 to its maximum heating effectiveness.

All of the flames remain lighted until the torch 63 reaches the position shown in Fig. 8 where the thickness of the work-piece begins to decrease. The flames 71' which were the last to be lighted are turned out by operation of the

cams to close the valve through which the oxy-fuel gas mixture is supplied to these flames.

When the torch reaches a section where the thickness of the work-piece has decreased still further, the flames 12' are extinguished by cutting off their supply of gas and the torch continues across the remainder of the work with only one row of heating flames 13' and the quenching jets 14'.

The torch 63 with three rows of heating flames is illustrative only. Two, or four, or even more groups of flames can be used, and it is not necessary that the groups be arranged in separate rows. For example, alternate jets of a single row might be supplied from separate distributing chambers and comprise different groups. The number of flames in the different groups need not be the same. Where the thickness of the work increases gradually, it is desirable to increase the heating effectiveness of the torch by smaller increments than is possible with the torch 63 where the turning-on of the second group of flame jets doubles the number of flames. For a rather rapid and very large change in section, as in the work-piece 64, large increments in the flame system are desirable.

The cams controlling the flames of the torch 63 in Figs. 2-9 are designed to vary the heating effect of the torch in a manner that compensates for the increase in the mass of metal in the center of the work-piece, and that produces a substantially uniform depth of hardness along the full length of the metal treated by the torch.

Various changes and modifications can be made in the invention, and some features of the invention can be used without others.

I claim:

1. The method of flame hardening a metal work-piece, which method comprises heating a section of the work-piece above its critical temperature by applying intense heat to the surface of that section with a number of separate heat sources, starting the operation of some of said heat sources ahead of others to apply heat for longer periods to regions where the mass of the work-piece is heavier than at other regions, and quenching the work-piece while it is heated above its critical temperature.

2. In the flame hardening of a metal work-piece, the improvement which comprises heating the section to be hardened by means of heating agencies applied simultaneously along the entire length of said section until the metal is heated above its critical temperature for a predetermined depth, but subjecting regions where the work-piece is of greater thickness to sufficient preliminary local heating to compensate for and reduce the addition conduction losses to the mass of metal in the region of greater thickness so that the work-piece is heated above its critical temperature for a substantially uniform depth by the simultaneous action of the heating agencies.

3. The method of flame hardening a metal work-piece that is not of uniform thickness throughout the length of the section to be hardened, which method comprises heating the regions of greater thickness first by local application of oxyacetylene heating flames to the surface of the work-piece at the thicker regions, subsequently applying oxyacetylene heating flames to the remainder of the surface of the section to be hardened while continuing the heating of the thicker regions, coordinating the time and intensity of the heating at different regions so that the entire section to be hardened is

heated above the critical temperature of the metal for a substantially uniform depth at approximately the same time, and with the metal at this elevated temperature applying quenching jets to the entire section.

4. The method of hardening a generally cylindrical work-piece that is of non-uniform wall thickness, which method comprises rotating the work-piece about its axis during the entire hardening operation, applying heating flames first to the surface where the wall is of greatest thickness, and subsequently to the entire length of the wall to be hardened with the time and intensity of the heating at the different regions coordinated to heat the different parts of the wall above the critical temperature of the metal for a substantially uniform depth at approximately the same time, discontinuing the heating and immediately thereafter applying a quenching fluid to the rotating work-piece throughout the length of the wall to be hardened.

5. The method of flame hardening a metal work-piece that is not of uniform thickness throughout the length of the section to be hardened, which method comprises producing relative movement of the work-piece and a system of flame jets that extend transversely of the direction of said movement, disposing the flame jets so that some of said flame jets heat the same portion of the work-piece during said relative movement, supplying fuel for different groups of the flame jets from separate distributing chambers, changing the heating effectiveness of the system of flame jets by extinguishing certain of the flame jets during the heating operation, causing the flame jets to be extinguished by shutting off fuel to the distributing chamber that supplies the group to which those flame jets belong, and controlling the extinguishment of the flame jets in accordance with a predetermined sequence that compensates for differences in heat losses at regions of the surface where the underlying metal of the work-piece is of different thickness.

6. The method of flame hardening a work-piece that varies in thickness along its length, which method comprises progressively moving at a substantially uniform speed a system of heating flames along the length of the work-piece with a plurality of said heating flames in positions to heat the same portion of the work-piece during the movement of said system lengthwise of the work-piece, following said system of heating flames closely by a system of quenching jets, and increasing and decreasing the number of heating flames in said system in accordance with changes in the thickness of the work-piece.

7. The method of progressively hardening a work-piece comprising moving a multi-jet system of heating flames along the length of the work-piece with the flame jets in a plurality of rows extending transversely of the direction of their movement along the work, following close behind the heating flame jets with a transversely extending row of quenching jets, and varying the heat developed by the flame system by cutting off the supply of fuel to different numbers of groups of the flame jets to compensate for various reductions in the thickness of the work-piece at regions along its length, and choosing the flame jets for extinguishment so as to leave the system of heating flames substantially unchanged in length transverse of the work-piece.

8. In flame hardening apparatus, torch means with a number of groups of jet orifices for direct-

ing heating flames against a section of a work-piece, said torch means having separate distributing chambers for the respective groups of flame jet orifices, a shut-off valve controlling the supply of fuel to each of the separate distributing chambers, and automatic valve-operating means for actuating said valves at predetermined times during a flame hardening operation to shut off or turn on the gas to said distributing chambers.

9. Flame hardening apparatus including in combination torch means with groups of flame jet orifices and a separate distributing chamber for each group of orifices, a valve for controlling the supply of gas to each distributing chamber, a cam associated with each of the valves for causing that valve to open and close, said cams being shaped and related with each other in accordance with variations in the thickness of a particular work-piece that is to be hardened, and automatic means for rotating the cams in unison and at a speed correlated with the heating operation to vary the heat developed by the torch means in a manner that compensates for differences in the conduction heat losses at regions of different thickness.

10. Flame hardening equipment including a torch block with separate distributing chambers therein extending in different directions, and a group of jet orifices opening from each of said chambers, and a separate shut-off valve for controlling the supply of gas to each chamber.

11. Flame hardening equipment including a torch block with three or more separate distributing chambers therein, some of which extend in different directions and a group of jet orifices opening from each of said chambers, a conduit for supplying quenching fluid to one of the distributing chambers, and other conduits for supplying fuel gas to the other chambers, and inde-

pendent shut-off valves in series with all of said conduits.

12. In a flame hardening apparatus, a torch block for heating a section of a work-piece, two rows of jet orifices opening through the top face of the torch block, one row extending longitudinally and the other transversely on the torch block, separate distributing chambers for supplying gas to each of said rows of jet orifices, separate valves for controlling the supply of gas to each of said chambers, and means for operating the valves.

13. Flame hardening apparatus comprising torch means with different groups of flame jet orifices supplied with gas from different distributing chambers, valves controlling the supply of gas to the respective chambers, means for moving the torch means, and means responsive to the displacement of the torch lengthwise of a work-piece for operating the valves, said means including one or more cams designed to control the valves in accordance with variations in the thickness of the work-piece.

14. Flame hardening equipment including in combination a support, means carried by the support and comprising a number of heating agencies for heating a work-piece, a plurality of said heating agencies being in positions to heat the same portion of the work-piece during movement of the support lengthwise of the work-piece, mechanism for moving the support lengthwise along the work-piece, and means responsive to such movement of the support for controlling the operation of the heating means to cause different numbers of said agencies to heat the same portion of the work-piece at different regions lengthwise of said work-piece.
